MINING MACHINE

William W. Sloane, Chicago, Ill., assignor to
Goodman Manufacturing Company, Chicago,
Ill., a corporation of Illinois

Application July 14, 1930, Serial No. 467,745
Renewed October 6, 1934

33 Claims. (Cl. 262—28)

This invention relates to improvements in mining machines and more particularly to machines of the truck mounted type having projecting kerf cutting elements thereon for making vertical and shearing cuts in the mine wall.

This invention has, among other objects, to provide a new and improved mining machine particularly adapted for operation in coal mines which may cut a horizontal kerf adjacent the mine floor or at various elevations with respect thereto, and which may also cut a vertical or shearing kerf without withdrawing the horizontal cutting element from the coal.

In carrying out my invention, I utilize a machine of the truck mounted type having a cutter arm adapted to cut a horizontal kerf in the mine wall, which machine may be similar to that disclosed in a prior application, Serial No. 402,505, of William T. McCullough, filed October 25, 1929, 10 which issued as Patent No. 1,938,850, December 12, 1933, but which has, in addition, an extensible and retractable cutting element mounted thereon for making a vertical cut when the horizontal cutting element is dumped in a mine wall.

20 My invention may be more clearly understood with reference to the accompanying drawings wherein:

Figure 1 is a top plan view of one embodiment of my invention with parts broken away and in section;

Figure 2 is a side elevation of the device shown in Figure 1 with certain parts broken away and in section;

Figure 3 is a side elevation of the device shown in Figure 1 taken on the opposite side of the machine from Figure 2 with certain parts broken away and in section;

Figure 4 is a partial enlarged fragmentary sectional view taken on line 4—4 of Figure 1;

Figure 5 is an enlarged partial fragmentary plan view of the machine with parts broken away and in section to more clearly show the details of my invention;

Figure 6 is a partial fragmentary sectional view taken on line 6—6 of Figure 5;

Figure 7 is an enlarged partial fragmentary sectional view taken on line 7—7 of Figure 5;

Figure 8 is a schematic wiring diagram of the motors for the undercutting and shearing elements; and

Figures 9, 10, 11, 12, 13 and 14 are diagrammatic views of the machine showing the various cutting positions thereof.

Like numerals refer to like parts throughout the various figures.

Referring now in particular to the drawings, the embodiment of my invention illustrated includes a truck 1 mounted on track wheels 2 and axles 3, having a turntable 4 thereon. A horizontally disposed cutting element 5, adapted to cut a horizontal kerf in the mine wall, is mounted on the turntable 4 for movement therewith. The horizontally disposed cutting element 5 is trunnioned on the turntable 4 on a transverse axis near the forward end thereof and offset to one side of the center of said turntable and is yieldably supported at its rearward end on said turntable in a usual manner for adjusting the position of said cutting element with respect to said turntable. An extensible and retractable cutting element 7, movable in a vertical plane to cut a shearing kerf in the mine wall, is mounted on the turntable 4 to one side of the horizontally disposed cutting element 5.

The turntable 4 is rotated by means of a motor 9 on the truck 1 near the rearward end thereof through suitable reduction gearing which herein comprises a motor pinion 10, a spur gear 11 driven thereby, a transverse shaft 12 rotated by said gear, and a worm and worm gear drive indicated at 13 for operatively connecting said transverse shaft with a vertical shaft 14. A spur gear 15 is fixed to the lower end of said vertical shaft and meshes and drives a spur gear 16 which drives a spur gear 17 coaxial with the spur gear 16, which spur gear meshes with teeth 18 on the outer periphery of said turntable for rotating said turntable.

The truck 1 may be propelled about the mine at either a high speed or a low feeding speed by means of the motor 9 by means of a suitable chain and sprocket drive (not shown) driven by a drive sprocket 19, which drive sprocket as herein shown, is driven from the transverse shaft 12 through a spur gear reduction drive generally indicated at 21 in the usual manner.

The horizontally disposed cutting element 5 is similar to that disclosed in the aforementioned prior application of William McCullough so will only herein be described insofar as is necessary to clearly illustrate my present invention. Said cutting element includes a motor 23 which is herein preferably shown as being an electric motor having a cutter frame 24 projecting forwardly therefrom beyond the boundaries of the truck 1. A cutter head 25 is suspended beneath the cutter frame 24 and is movable vertically with respect thereto in guides 26, 26 and has a cutter bar 27 projecting forwardly therefrom. Said cutter bar is mounted for pivotal movement

about a vertical axis disposed adjacent its rearward end and forwardly of said truck for adjustment for cutting along a mine bottom in front of and to each side of the track and has a cutter chain 28 movable thereabout. Said cutter chain is driven from the motor 23 by a suitable gear train generally indicated at 22 in a usual manner. Suitable locking means are provided for locking said cutter bar in various positions of angular adjustment with respect to said cutter frame which may be of a usual construction so will not herein be shown in detail.

Referring now in particular to the details of the extensible and retractable cutting element 7 which forms one of the novel features of my invention, said cutting element includes a motor 29 slidable longitudinally of the turntable 4 in guides generally indicated at 30, fixed to said turntable and disposed in parallel relation to the cutting element 5. Said guides include a member 31 fixed on said turntable in a suitable manner as is shown in Figure 7, which member projects forwardly therefrom beyond the boundaries of the truck 1. An outer side 32 of the member 31 extends vertically upwardly and inwardly to engage the outside and a portion of the top of the motor 29. An inner side 33 of the member 31 extends vertically upwardly from said member and has a groove 34 formed therein engaged by a foot 35 integral with the motor 29. A rack 36 is provided on the top portion of the inner side 33 of the member 31, which rack is engaged by a pinion 37 on a stub shaft 38 for moving the motor 29 and cutting element 7 along the member 31 in the guides 30.

A portion 39 of the casing for the motor 29 extends upwardly and outwardly therefrom and forms a bearing support for various parts of the cutting element 7. A cutter bar supporting member 40 is journaled in the portion 39 for pivotal movement with respect thereto about a transverse axis. A flange 41 extends outwardly from the portion 39 of the casing of the motor 29 and abuts a shoulder 42 formed in the cutter bar supporting member 40. A ring 43 is fastened to said cutter bar supporting member and abuts the inner face of the flange 41 to prevent lateral movement of said cutter bar supporting member 40 with respect to the portion 39. This ring may be held to said cutter bar supporting member by any suitable means, but as herein shown said ring is held to said cutter bar supporting member by means of cap screws 44 (see Figures 4 and 5).

The cutter bar supporting member 40 extends forwardly from the portion 39 of the casing for the motor 29 and has a cutter bar 45 fixed thereto having a cutter chain 46 movable thereabout. A vertically disposed arcuate rack 47 is fixed on the forwardmost portion of said cutter bar supporting member and has internally cut teeth facing the rearward end of said cutting element. Said arcuate rack is engaged by a pinion 48 on the end of a transverse shaft 49 driven from the motor 29 in a manner which will hereinafter be more fully described. Thus rotation of the pinion 48 causes movement of the arcuate rack 47 and moves the cutter bar 45 about the axis of connection of said cutter bar supporting member to the portion 39 of said motor casing.

Referring now in particular to the means for driving the cutter chain 46 from the motor 29, said motor is provided with a bevel armature pinion 50 which meshes with and drives a bevel gear 51 on a transverse shaft 53. A spur gear

55 is fixed on said transverse shaft and meshes with and drives a spur gear 56 on a transverse shaft 57 located above the transverse shaft 53. The transverse shaft 57 is journaled within a bored portion 58 of the cutter bar supporting member 40 by suitable means herein shown as ball bearings of an ordinary construction (see Figure 5).

A member 60 is keyed on the transverse shaft 57 and journaled in the bored portion 58 of the cutter bar supporting member 40 and is held to said transverse shaft by means of a nut 62. A collar 65 abuts the outer surface of the cutter bar supporting member 40 while a sprocket 63 is fixed on the member 60 and is interposed between the outer end of said collar and a flange 64 integral with the outer end of said member. The sprocket 63 meshes with the cutter chain 46 for driving said cutter chain upon rotation of the motor 29.

Referring now in particular to Figures 5 and 7 and the details of the mechanism for driving the pinions 37 and 48 for moving the cutting element along the guides 30 or for raising or lowering said cutting element about the axis of the transverse shaft 57, a bevel pinion 67 is fixed on the inner end of said transverse shaft and is held thereto by means of a nut 68. This bevel pinion meshes with and drives a bevel gear 69 keyed on a longitudinally extending horizontal shaft 70. A spur pinion 71 is fixed on the shaft 70 and meshes with and drives a spur pinion 73 on a longitudinally extending stud shaft 74 located above the shaft 70. A spur gear 75 is keyed near the opposite end of the longitudinally extending horizontal shaft 70 adjacent the inner end of a bearing support 76 for said shaft. The spur pinion 73 meshes with and drives spur gears 77 and 78 on opposite sides thereof, while the spur gear 75 meshes with and drives spur gears 79 and 80 on opposite sides thereof respectively in opposite directions to the spur gears 77 and 78.

The spur gear 77 is fixed on the rearward portion of a casing 81 for a clutch 82. The casing 81 is freely mounted on a shaft 83 and is journaled in a bearing support 84. The clutch 82 is a friction clutch of an ordinary construction so will not herein be described in detail and has operative connection with the shaft 83 for driving said shaft through a clutch collar 85 feathered on said shaft.

Similarly the spur gear 79 is fixed on a casing 86, freely mounted on its hub in a suitable bearing member and a bored portion of the hub of said casing forms a bearing for the shaft 83. The casing 86 forms a driving member for a clutch 88 which is a suitable friction disc clutch of an ordinary construction so will not herein be described in detail. The clutch 88 is operatively connectible with the shaft 83 for driving said shaft by means of the clutch collar 85.

When the clutch collar 85 is in a central position on the shaft 83 intermediate the clutches 82 and 88, neither of said clutches have driving engagement with said shaft. Thus when the clutch collar 85 is moved adjacent the clutch 82, the shaft 83 is driven in one direction through said clutch and when the clutch collar 85 is moved adjacent the clutch 88, the shaft 83 is driven in an opposite direction through the clutch 88. A suitable system of levers is provided to move the clutch collar along the shaft 83 to operatively engage either the clutch 82 or the clutch 88 with the shaft 83, which system of levers is of an ordinary construction so is not herein shown. Thus a means has been provided for driving the shaft

83 in opposite directions at frictionally controlled speeds without reversal of the motor 29.

A worm 89 is keyed near the forward end of the shaft 83 and meshes with and drives a worm gear 90 keyed on a sleeve 91 freely mounted on the transverse shaft 49. A spur gear 93 is herein shown as being formed integral with the sleeve 91 and meshes with and drives the pinion 37 on the stud 38 (see Figure 6). Rotation of the pinion 37 causes the vertically disposed cutting element to move in the guides 30 and said movement is controlled by the friction clutches 82 and 83 so that said cutting element may be moved in opposite directions along the rack 36 at frictionally controlled speeds without reversal of the motor 29 to extend said cutter bar beyond the truck or retract said cutter bar with respect to said rack for cutting a vertical kerf in the mine wall.

The spur gear 78 is fixed on the rearward portion of a casing 95 for a clutch 97 which casing 95 is freely mounted on a longitudinal shaft 96 in a manner similar to which the clutch casing 81 is mounted on the longitudinal shaft 83. The clutch casing 95 forms a driving member for the clutch 97 which clutch is a friction clutch of an ordinary construction and is operatively connected to the shaft 96 for driving said shaft in a usual manner by means of a clutch collar 99 feathered to said shaft. Similarly the spur gear 80 is mounted on a clutch casing 100 for a clutch 101. This clutch is operatively connected to the longitudinal shaft 96 by means of the clutch collar 99 in a usual manner for driving said shaft. The construction of the clutches 97 and 101 is similar to the construction of the clutches 82 and 83 and their method of operation is the same as the method of operation of said aforementioned clutches; as, for example, when one clutch is operatively engaged with the shaft 96 to drive said shaft in one direction the opposite clutch is disengaged from said shaft. The opposite clutch also may be connected to said shaft to drive said shaft in an opposite direction upon disengagement of said first mentioned clutch from said shaft.

A worm 103 (see Figures 5 and 6) is keyed on the longitudinal shaft 96 near the forward end thereof and meshes with and drives a worm gear 104 keyed on the transverse shaft 49 for driving said shaft. It may thus be seen that rotation of the shaft 48 drives the pinion 48 which moves the rack 47 and cutter bar 45 with respect to said pinion about the axis of the shaft 57 to vertically move said cutter bar. The direction of vertical movement of the cutter bar 45 may be reversed by engaging either of the clutches 97 or 101 with the shaft 96.

It may thus be seen that a novel driving arrangement has been provided for moving the cutting element 7 along the rack 36 to sump the cutter bar 45 into the coal and for vertically moving said cutter bar about the axis of the shaft 57 when sumped in the coal to make a vertical cut in the mine wall, and that said means are driven from a single motor so that the longitudinal and vertical movements are independent of each other and so that both of said movements may be independently reversed without reversal of the motor 29.

The motor 23, which operates the horizontally disposed cutting element 5, is electrically interconnected with the motor 29 which operates the extensible and retractable cutting element 7 by means of a switch 105 of an ordinary construc-

tion and diagrammatically illustrated in Figure 8, so that both of said motors may be operated from a single controller 106 and so that only one of these motors may be operated at a time. The controller 106 controls the operation of the motors 23 and 29 in a usual manner and obtains power from a cable reel 107 through suitable conductors in a usual manner so that the details of operation and construction of said controller are not herein described in detail. The purpose of so interconnecting the cutting motors is to provide a simplified electric connection whereby one controller may operate both motors and to prevent operation of one cutting element while the other cutting element is operative to serve as a safety feature and prevent breakage of the various parts which would necessarily arise upon the operation of both cutting elements simultaneously.

Referring now in particular to Figures 9 to 14, inclusive, which figures diagrammatically show the machine of my invention in various cutting positions, the horizontal cutter bar 27 is sumped in the mine wall in a usual manner as is shown in Figure 9 and may be moved across the coal face by the turntable 4, or along a coal face by means of the truck when cutting a slabbing kerf. When said cutter bar is cutting across the coal face, the cutter bar 45 is in a retracted position in the guides 30. When it is desired to make a vertical or shearing cut, movement of the cutter bar 27 across the face is stopped and the cutter bar 45 is usually raised by the pinion 48 and arcuate rack 47 until the upper forward end of the cutter bar abuts the mine roof as indicated by dotted lines in Figure 12. Said cutter bar may then be extended forwardly along the guides 30 and moved into the coal by means of the pinion 37 and rack 36. When said cutter bar has been fed into the coal the desired distance, the pinion 37 is disconnected from the motor 29 to stop longitudinal movement of said cutter bar into the coal and said cutter bar is lowered in the coal until it reaches the mine bottom as is shown in Figure 13. Said cutter bar is then withdrawn from the coal by means of the pinion 37 and rack 36 (see Fig. 14), thus cutting a vertical kerf in the mine wall. Figures 9 and 10 show the machine cutting in a mine entry while Figure 11 shows the machine making a slabbing cut along the mine wall. It may thus be seen that the machine of my invention is adapted for use in entry driving as well as for use in cutting along mine faces and that a shearing cut may be made in the mine wall when desired without withdrawing the cutter bar 27 from the coal.

It may now be seen that a new and improved mining machine has been provided which is a combination mining and shearing machine and is so arranged that a shearing cut may be made in the mine wall when desired without withdrawing the vertical cutting element from the coal. This provides a simplified form of mining machine and facilitates the cutting and mining operation in that both the vertical and horizontal cuts may be made without withdrawing the horizontal cutting element from the coal.

Although I have herein shown and described one form in which my invention may be embodied, it will be understood that the construction thereof and the arrangement of the various parts may be altered without departing from the spirit and scope thereof. Furthermore, I do not wish to be construed as limiting myself to the specific embodiment illustrated in the drawings,

excepting as it may be limited by the appended claims.

I claim as my invention:

1. In a mining machine, a support, cutting mechanism thereon including a horizontal swinging projecting cutter bar adapted to cut a horizontal kerf in the mine wall by swinging movement with respect to said support about a vertical axis and a horizontally extensible and retractable cutter bar adapted to cut a vertical kerf in the mine wall by horizontal translational movement with respect to said support and pivotal movement about a horizontal axis. 5
2. In a mining machine, a support, cutting mechanism thereon including a horizontal swinging projecting cutter bar adapted to cut a horizontal kerf in the mine wall by swinging movement with respect to said support about a vertical axis and a vertical horizontally extensible and retractable cutter bar adapted to cut a vertical kerf in the mine wall by horizontal translational movement with respect to said support and pivotal movement about a horizontal axis, said vertical cutter bar being supported adjacent said horizontal cutter bar and movable longitudinally of said horizontal cutter bar. 10
3. In a mining machine, horizontal and shearing cutting mechanism therefor including a cutting element having a swinging projecting cutter bar adapted to cut a horizontal kerf in the mine wall and a horizontally extensible and retractable cutting element adapted to cut a vertical kerf in the mine wall having a vertically arranged cutter bar having a cutter chain movable thereabout, gear reduction mechanism for driving said cutter chain about said cutter bar, said vertical cutter bar being closely adjacent said horizontal cutting element and said gear reduction mechanism being disposed on the outer side of said horizontal kerf cutting element and extending away from said horizontal cutting element. 15
4. In a mining machine, horizontal and shearing cutting mechanism therefor including a cutting element having a swinging projecting cutter bar adapted to cut a horizontal kerf in the mine wall and a horizontally extensible and retractable cutting element adapted to cut a vertical kerf in the mine wall, said extensible and retractable cutting element including a vertical cutter bar disposed adjacent said horizontal cutting element and mechanism for extending said extensible and retractable cutting element disposed to one side thereof away from said horizontal cutting element. 20
5. In a mining machine, a track-mounted truck, horizontal and vertical cutting mechanism supported on said truck including a forwardly projecting cutter bar mounted for pivotal movement about a vertical axis disposed forwardly of said truck and adapted to cut a horizontal kerf adjacent the mine bottom, and a second cutter bar arranged to one side of said first cutter bar and pivotally mounted on a support for movement in a vertical plane, said support being extensible and retractable with respect to said truck to move said cutter bar horizontally and position said cutter bar to cut a kerf intersecting the cutting plane of said first-mentioned cutter bar. 25
6. In a track-mounted mining machine, a truck, a turntable on said truck, power means for moving said truck at feeding and traveling speeds and power means for swinging said turntable, and horizontal and shearing cutting mechanism on said turntable including a projecting cutter bar 30
- adapted to cut a horizontal kerf in a mine wall, and a vertical cutter bar arranged along side of said first-mentioned cutter bar for translational movement with respect thereto in a horizontal plane and pivotal movement in a vertical plane for cutting a vertical kerf in the mine wall. 5
7. In a truck mounted mining machine, a turntable, and horizontal and shearing cutting mechanism thereon including a horizontal cutter bar adapted to cut a horizontal kerf adjacent the mine bottom or at various elevations with respect thereto and another cutter bar pivotally movable about a horizontal axis adjacent its rearward end adapted to cut a shearing kerf in the mine wall. 10
8. In a truck mounted mining machine, a turntable, and horizontal and shearing cutting mechanism thereon including a horizontal cutter bar adapted to cut a horizontal kerf adjacent the mine bottom or at various elevations with respect thereto and a horizontally extensible and retractable cutter bar adapted to cut a vertical kerf in the mine wall. 15
9. In a truck mounted mining machine, a turntable, and horizontal and shearing cutting mechanism mounted on said turntable including a horizontal cutter bar offset from the axis thereof and adapted to cut a horizontal kerf adjacent the mine bottom, and a horizontally extensible cutter bar mounted on said turntable adjacent said horizontal cutter bar and movable longitudinally of said horizontal cutter bar. 20
10. In a truck mounted mining machine, a turntable, and horizontal and shearing cutting mechanism mounted on said turntable including a horizontal cutting element offset from the axis thereof and having a forwardly projecting depending cutter bar adapted to cut a horizontal kerf adjacent the mine bottom, and a horizontally extensible and retractable cutting element adjacent said horizontal cutting element having a cutter bar thereon, movable longitudinally of said horizontal cutting element. 25
11. In a truck mounted mining machine, a turntable, and horizontal and shearing cutting mechanism mounted on said turntable including a horizontal cutting element offset from the axis thereof and having a forwardly projecting depending cutter bar adapted to cut a horizontal kerf adjacent the mine bottom, and a horizontally extensible and retractable cutting element adjacent said horizontal cutting element comprising a motor, a cutter bar pivotally movable with respect to said motor about a horizontal axis, and means connectible with said motor for moving said cutter bar longitudinally of said first mentioned horizontal cutting element. 30
12. In a truck mounted mining machine, a turntable, horizontal and shearing cutting mechanism thereon including a horizontal cutting element having a forwardly projecting cutter bar adapted to cut a horizontal kerf adjacent the mine bottom, and a horizontally extensible and retractable cutting element adjacent said horizontal cutting element including a motor, a cutter bar pivotally movable with respect to said motor about a horizontal axis, means connectible with said motor for moving said cutter bar about said horizontal axis and means connectible with said motor for moving said second mentioned cutting element longitudinally with respect to said first mentioned horizontal cutting element. 35
13. In a truck mounted mining machine, a turntable, a horizontal and shearing cutting mechanism thereon including a horizontal cutting element having a forwardly projecting cut- 40
- 45
- 50
- 55
- 60
- 65
- 70

- ter bar adapted to cut a horizontal kerf adjacent the mine bottom, and a horizontally extensible and retractable cutting element adjacent said horizontal cutting element including a motor, a cutter bar pivotally movable with respect to said motor about a horizontal axis, means connectible with said motor for reciprocably moving said cutter bar about said horizontal axis and means operable independently of said means for moving said cutter bar about said horizontal axis and connectible with said motor for reciprocably moving said second mentioned cutting element longitudinally with respect to said first mentioned horizontal cutting element.
14. In a track mounted mining machine, a truck, horizontal and shearing cutting mechanism on said truck including a projecting cutter bar adapted to cut a horizontal kerf in the mine wall by movement of the truck with respect to the coal face and swinging movement of said cutter bar across the front of the truck and a pivotally movable horizontally extensible and retractable cutter bar adapted to cut a vertical kerf in the mine wall by movement of said cutter bar with respect to the truck and swinging movement of said cutter bar in a vertical plane.
15. In a track mounted mining machine, a truck, horizontal and shearing cutting mechanism on said truck including a projecting cutter bar adapted to cut a horizontal kerf in the mine wall by movement of the truck with respect to the coal face and swinging movement of said cutter bar across the front of the truck and a pivotally movable horizontally extensible cutter bar adapted to cut a vertical kerf in the mine wall mounted on said truck adjacent said horizontal cutter bar and movable longitudinally of said horizontal cutter bar.
16. In a track mounted mining machine, a truck, horizontal and shearing cutting mechanism on said truck including a cutting element having a projecting cutter bar adapted to cut a horizontal kerf in the mine wall by movement of the truck with respect to the coal face and swinging movement of said cutter bar across the front of the truck and a pivotally movable horizontally extensible and retractable cutting element adjacent said first mentioned cutting element having a projecting cutter bar thereon movable longitudinally of said first mentioned cutting element.
17. In a track mounted mining machine, a truck, a turntable on said truck, and horizontal and shearing cutting mechanism on said turntable including a projecting cutter bar adapted to cut a horizontal kerf in a mine wall, and another cutter bar movable in a vertical plane about a horizontal pivotal axis adapted to cut a vertical kerf in the mine wall.
18. In a track mounted mining machine, a truck, a turntable on said truck, and horizontal and shearing cutting mechanism on said turntable including a projecting cutter bar adapted to cut a horizontal kerf in a mine wall, and a horizontally extensible and retractable cutter bar adapted to cut a vertical kerf in the mine wall.
19. In a track mounted mining machine, a truck, a turntable on said truck, and horizontal and shearing cutting mechanism on said turntable including a projecting cutter bar adapted to cut a horizontal kerf in a mine wall, and a horizontally extensible and retractable cutter bar mounted on said turntable adjacent one side of said projecting cutter bar and movable longitudinally of said projecting cutter bar.
20. In a track mounted mining machine, a truck, a turntable on said truck, and horizontal and shearing cutting mechanism on said turntable including a horizontal cutting element offset from the axis of said turntable and having a forwardly projecting cutter bar thereon adapted to cut a horizontal kerf in the mine wall and a horizontally extensible and retractable cutting element having a cutter bar thereon movable longitudinally of said horizontal cutting element for cutting a vertical kerf in the mine wall.
21. In a truck mounted mining machine, a turntable, horizontal and shearing cutting mechanism thereon including a horizontal cutting element having a forwardly projecting cutter bar adapted to cut a horizontal kerf in the mine wall, and a horizontally extensible and retractable cutting element adjacent said horizontal cutting element movable longitudinally with respect thereto, said horizontally extensible and retractible cutting element comprising a motor, a cutter bar pivotally movable about a horizontal axis with respect to said motor, and means connectible with said motor for reciprocably moving said second mentioned cutting element longitudinally of said horizontal cutting element and reciprocably moving said cutter bar about said horizontal axis independently or simultaneously with horizontal movement of said second mentioned cutting element comprising a longitudinal shaft having connection with said motor, and a pair of parallel shafts adapted to be driven from said longitudinal shaft in reverse directions without reversing the direction of rotation of said longitudinal shaft.
22. In a truck mounted mining machine, a turntable, horizontal and shearing cutting mechanism thereon including a horizontal cutting element having a forwardly projecting cutter bar adapted to cut a horizontal kerf in the mine wall, and a horizontally extensible and retractable cutting element adjacent said horizontal cutting element movable longitudinally with respect thereto, said horizontally extensible and retractible cutting element comprising a motor, a cutter bar pivotally movable about a horizontal axis with respect to said motor, and means connectible with said motor for reciprocably moving said second mentioned cutting element longitudinally of said horizontal cutting element and reciprocably moving said cutter bar about said horizontal axis independently or simultaneously with horizontal movement of said second mentioned cutting element comprising a longitudinal shaft having connection with said motor, and a pair of parallel shafts adapted to be driven from said longitudinal shaft in reverse directions without reversing the direction of rotation of said longitudinal shaft, and a transverse shaft forwardly of said motor operatively connectible with one of said parallel shafts.
23. In a truck mounted mining machine, a turntable, horizontal and shearing cutting mechanism thereon including a horizontal cutting element having a forwardly projecting cutter bar adapted to cut a horizontal kerf in the mine wall, and a horizontally extensible and retractable cutting element adjacent said horizontal cutting element movable longitudinally with respect thereto, said horizontally extensible and retractible cutting element comprising a motor, a cutter bar pivotally movable about a horizontal axis and means connectible with said motor for reciprocably moving said second mentioned cutting element longitudinally of said horizontal cutting element.

- 5 cutting element and reciprocably moving said cutter bar about said horizontal axis independently of or simultaneously with horizontal movement of said second mentioned cutting element 5 comprising a longitudinal shaft having connection with said motor, a pair of parallel shafts adapted to be driven from said longitudinal shaft in reverse directions without reversing the direction of rotation of said longitudinal shaft, and 10 a transverse shaft forwardly of said motor operatively connectible with one of said parallel shafts, and having coaxial gear means freely mounted thereon driven from said other parallel shaft.
- 15 24. In a truck mounted mining machine, a turntable, horizontal and shearing cutting mechanism thereon including a horizontal cutting element having a forwardly projecting cutter bar adapted to cut a horizontal kerf in the mine wall, 20 and a horizontally extensible and retractable cutting element adjacent said horizontal cutting element movable longitudinally with respect thereto, said horizontally extensible and retractable cutting element comprising a motor, a cutter bar 25 pivotally movable about a horizontal axis with respect to said motor, and means connectible with said motor for reciprocably moving said second mentioned cutting element longitudinally of said horizontal cutting element and reciprocably moving said cutter bar about said horizontal axis independently of or simultaneously with horizontal movement of said second mentioned cutting element, an arcuate rack having fixed connection with said cutter bar, a longitudinally extending rack fixed to said turntable 30 parallel to said horizontal cutting element, a transverse shaft having means coaxial therewith for moving said rack about the pivotal axis of said cutter bar and having other means coaxial therewith for moving said second mentioned cutting element with respect to said longitudinally extending rack, and means for driving said first and second mentioned means simultaneously with or independently of each other comprising a plurality of parallel driving shafts having operative connection with said motor.
- 35 27. In a truck mounted mining machine, a turntable, horizontal and shearing cutting mechanism thereon including a horizontal cutting element having a forwardly projecting cutter bar 35 adapted to cut a horizontal kerf in the mine wall, and a horizontally extensible and retractable cutting element adjacent said horizontal cutting element movable longitudinally with respect thereto, said horizontally extensible and retractable cutting element comprising a motor, a cutter bar pivotally movable about a horizontal axis with respect to said motor, and means connectible with said motor for reciprocably moving said second mentioned cutting element longitudinally of said horizontal cutting element and reciprocably moving said cutter bar about said horizontal axis independently of or simultaneously with horizontal movement of said second 40 mentioned cutting element, an arcuate rack having fixed connection with said cutter bar, a longitudinally extending rack fixed to said turntable parallel to said horizontal cutting element, a transverse shaft having means coaxial therewith for moving said rack about the pivotal axis of said cutter bar, and for moving said second mentioned cutting element with respect to said longitudinally extending rack.
- 45 25. In a truck mounted mining machine, a turntable, horizontal and shearing cutting mechanism thereon including a horizontal cutting element having a forwardly projecting cutter bar adapted to cut a horizontal kerf in the mine wall, and a horizontally extensible and retractable cutting element adjacent said horizontal cutting element movable longitudinally with respect thereto, said horizontally extensible and retractable cutting element comprising a motor, a cutter bar pivotally movable about a horizontal axis with respect to said motor, and means connectible with said motor for reciprocably moving said second mentioned cutting element longitudinally of said horizontal cutting element and reciprocably moving said cutter bar about said horizontal axis independently of or simultaneously with horizontal movement of said second mentioned cutting element, an arcuate rack having fixed connection with said cutter bar, a longitudinally extending rack fixed to said turntable parallel to said horizontal cutting element, a transverse shaft having means coaxial therewith for moving said rack about the pivotal axis of said cutter bar and having other means coaxial therewith for moving said second mentioned cutting element with respect to said longitudinally extending rack, and means for driving said first and second mentioned means simultaneously or independently of each other in reverse directions without reversal of said motor comprising a plurality of parallel driving shafts having operative connection with said motor.
- 50 28. In a truck mounted mining machine, a turntable, horizontal and shearing cutting mechanism thereon including a horizontal cutting element having a forwardly projecting cutter bar adapted to cut a horizontal kerf in the mine wall, and a horizontally extensible and retractable cutting element adjacent said horizontal cutting element movable longitudinally with respect thereto, said horizontally extensible and retractable cutting element comprising a motor, a cutter bar pivotally movable about a horizontal axis with respect to said motor, and means connectible with said motor for reciprocably moving said second mentioned cutting element longitudinally of said horizontal cutting element and reciprocably moving said cutter bar about said horizontal axis.
- 55 70 26. In a truck mounted mining machine, a turntable, horizontal and shearing cutting mechanism thereon including a horizontal cutting element having a forwardly projecting cutter bar adapted to cut a horizontal kerf in the mine wall, and a horizontally extensible and retractable cutting element adjacent said horizontal cutting element movable longitudinally with respect thereto, said horizontally extensible and retractable cutting element comprising a motor, a cutter bar pivotally movable about a horizontal axis with respect to said motor, and means connectible with said motor for reciprocably moving said second mentioned cutting element longitudinally of said horizontal cutting element and reciprocably moving said cutter bar about said horizontal axis.
- 60 75

- independently of or simultaneously with horizontal movement of said second mentioned cutting element, an arcuate rack having fixed connection with said cutter bar, a longitudinally extending rack fixed to said turntable parallel to said horizontal cutting element, a transverse shaft having means coaxial therewith for moving said rack about the pivotal axis of said cutter bar and having other means coaxial therewith
- 5 for moving said second mentioned cutting element with respect to said longitudinally extending rack, and means for driving said first and second mentioned means simultaneously with or independently of each other in reverse directions
- 10 without reversal of said motor comprising a plurality of parallel driving shafts having operative connection with said motor, and means for driving said shafts from said motor without reversal of said motor.
- 15 29. In a truck mounted mining machine, a turntable, cutting mechanism on said turntable adapted to cut a horizontal kerf adjacent the mine bottom including a motor and a depending cutter bar having a cutter chain movable thereabout, and other cutting mechanism on said turntable for cutting a shearing kerf in the mine wall without withdrawing said first mentioned cutter 10 bar from the mine wall comprising a horizontally extensible and retractable cutting element.
- 20 30. In a truck mounted mining machine, a turntable, cutting mechanism on said turntable adapted to cut a horizontal kerf adjacent the mine bottom or at various elevations with respect thereto including a motor, a cutter bar having a cutter chain movable thereabout driven from said motor, and a horizontally extensible and retractable cutting element adjacent said first mentioned cutting mechanism including a motor, a cutter bar having a cutter chain movable thereabout
- 25 driven from said motor and means for interconnecting said first and second mentioned motors to prevent driving one of said cutter chains while said other cutter chain is being driven.
- 30 31. In a truck mounted mining machine, a turntable, cutting mechanism on said turntable adapted to cut a horizontal kerf adjacent the mine bottom including a motor and a depending 30 cutter bar having a cutter chain movable thereabout, and other cutting mechanism on said turntable for cutting a shearing kerf in the mine wall without withdrawing said first mentioned cutter 20 bar from the mine wall comprising a horizontally extensible and retractable cutting element including a motor, a cutter bar arcuately movable in a vertical plane about a horizontal axis and having a cutter chain movable thereabout driven from 25 said motor.
- 35 32. In a truck mounted mining machine, a turntable, cutting mechanism on said turntable adapted to cut a horizontal kerf adjacent the mine bottom including a motor and a depending 35 cutter bar having a cutter chain movable thereabout, and other cutting mechanism on said turntable for cutting a shearing kerf in the mine wall without withdrawing said first mentioned cutter 20 bar from the mine wall comprising a horizontally extensible and retractable cutting element including a motor, a cutter bar arcuately movable in a vertical plane about a horizontal axis and having a cutter chain movable thereabout driven from 25 said motor.
- 40 33. In a truck mounted mining machine, a turntable, cutting mechanism on said turntable adapted to cut a horizontal kerf adjacent the mine bottom including a motor and a depending 40 cutter bar having a cutter chain movable thereabout, and other cutting mechanism on said turntable for cutting a shearing kerf in the mine wall without withdrawing said first mentioned cutter 35 bar from the mine wall comprising a horizontally extensible and retractable cutting element including a motor, a cutter bar arcuately movable in a vertical plane about a horizontal axis and having a cutter chain movable thereabout driven from 40 said motor, and means for interconnecting said first and second mentioned cutting mechanisms to prevent operation of one of said cutting mechanisms while said other cutting mechanism is in operation.
